His Attorney.

UNITED STATES PATENT OFFICE.

JAMES M. WEED, OF SCOTIA, NEW YORK, ASSIGNOR TO GENERAL ELECTRIC COMPANY, A CORPORATION OF NEW YORK.

ELECTRIC FURNACE.

Application filed March 23, 1926. Serial No. 96,843.

My invention relates to electric furnaces, more specifically to electric metal melting furnaces, and has for its object the provision of a simple, reliable and efficient electric furnace for melting metals in which provision is made for producing a circulation of the molten metal.

In carrying out my invention in one form I provide an electrically insulating partition in the melting crucible, this partition being spaced from the bottom of the crucible, and electrodes on opposite sides of the partition whereby an electric heating current can be passed through the metal.

For a more complete understanding of my invention reference should be had to the accompanying drawing in which Fig. 1 is a sectional view showing in somewhat diagrammatic fashion an electric melting furnace embodying my invention; Fig. 2 is a sectional view along the line 2-2 of Fig. 1 looking in the direction of the arrows; while Fig. 3 is a sectional view similar to Fig. 2 but showing a modified form of my invention.

Referring to the drawing, my invention in one form embodies a crucible 10 made of a suitable heat refractory and electrically insulating material, such as fire clay. This crucible may be provided with an outer protecting metallic jacket 11. A spout 12 is provided to facilitate pouring of the molten metal, and the crucible may be mounted on horizontal pivots in a well known manner to facilitate the pouring. The crucible 10 is arranged to provide a reservoir 13 for the molten charge which is connected at the bottom with an elongated reservoir 14 having a transverse sectional area much less than the transverse sectional area of the reservoir 13. As shown, reservoir 14 depends vertically from the bottom of the upper reservoir 13 although it may be inclined.

The crucible 10 is also provided with a vertical partition 15 extending centrally across the reservoirs 13 and 14. This partition is made of heat refractory electrically insulating material and it may be molded integrally with the crucible. It is joined with the side walls of the crucible down to the lower end of the reservoir 14 at which point a space 16 is provided between the lower end of the partition and the bottom of the crucible. The effect of the partition is therefore, to provide a U-shaped duct 17

which is connected at its ends with the bottom of the reservoir 13. At its upper end the partition 15 divides the reservoir 13 into two equal portions which are connected respectively with the ends of the U-shaped duct. Electrodes 18 and 19 are provided on opposite sides of the partition whereby an electric heating current may be passed from one electrode through the U-shaped duct back to the other electrode. The electrodes will be connected to a suitable source of electrical supply 20, for example, through a low voltage transformer 21.

In the operation of the furnace a sufficient amount of molten charge is provided in the crucible to fill the duct 17 and thus establish an electric circuit from one electrode to the other, whereby heat is generated by the current passed through the charge in the duct 17. A brisk circulation of the hotter metal in the duct 17 is produced by electromagnetic repulsion between the two upright lengths or legs of the U-shaped duct. This will be made clear when it is observed that the current in the two legs is flowing in opposite directions. There will, therefore, be an electromagnetic repulsive force between them, which force, acting on the molten metal, tends to force the metal toward the outer sides of the two legs, that is, toward the sides most remote from each other. This action results in an increased fluid pressure in the molten charge in the vicinity of these remotely situated sides, and since the metal is prevented from flowing downward by the closed bottom of the reservoir it flows upward along the remote sides of the branches, as indicated by the arrows, the cooler molten charge from the reservoir 13 flowing downward adjacent the sides of the partition 15 to take the place of the hotter metal. By means of this circulation the charge is maintained at a substantially uniform temperature, and the heat generated within the duct is delivered to the two portions of the reservoir 13 whereby additional cold charge fed into this reservoir will be quickly melted.

In the modified form of my invention shown in Fig. 3, the two legs of the U-shaped duct are displaced horizontally in the direction parallel to the partition 15. This arrangement brings the two most remote portions of these legs at the ends 22 and 23 of the transverse sections, with the result that the molten metal is forced upward in these

regions, and the colder metal flows downward in the regions most closely adjacent each other, i. e., the opposite ends 24 and 25. This provides for freer circulation since the two oppositely flowing streams of molten metal in each leg are in more remotely situated portions of the duct, whereas in the form shown in Figs. 1 and 2 these streams of molten metal are more closely adjacent to each other, being in regions separated by the least transverse sectional dimension of the duct.

While I have described my invention as embodied in concrete form and as operating in a specific manner in accordance with the provisions of the patent statutes, it should be understood that I do not limit my invention thereto since various modifications thereof will suggest themselves to those skilled in the art without departing from the spirit of my invention, the scope of which is set forth in the annexed claims.

What I claim as new and desire to secure by Letters Patent of the United States is:—

1. An electric furnace comprising a crucible providing a reservoir for the charge divided into a plurality of separate portions connected together at their bottoms through a duct having contiguous legs lying in parallel planes, and means for passing an electric heating current through the portion of the charge in said duct.

2. An electric furnace comprising a cruci-

ble providing a reservoir for the charge divided into a plurality of separate portions connected together at their bottoms through a duct having contiguous substantially parallel legs, and means for passing an electric heating current through the portion of the charge in said duct.

3. An electric furnace comprising a crucible providing a reservoir for the charge divided into two portions having their bottoms connected by a U-shaped duct, and electrodes in electrically conducting relation with the molten charge in said portion whereby a heating current can be passed through the portion of the charge in the duct from one electrode to the other.

4. An electric metal melting furnace comprising a crucible providing a reservoir for the charge, said reservoir being provided with a smaller elongated portion at the bottom, and an electrically insulating partition in said reservoir spaced from the bottom thereof dividing said reservoir and said smaller portion into two portions connected together at the bottom of said smaller portion, said smaller portion thereby constituting a U-shaped duct, and electrodes in contact with the molten metal on opposite sides of said partition for passing a heating current through the charge.

In witness whereof I have hereunto set my hand this 22nd day of March, 1926.

JAMES M. WEED.
